UNITED STATES PATENT OFFICE.

WILLIAM A. ELLIOT, OF YONKERS, NEW YORK, ASSIGNOR TO THE
BIGELOW CARPET COMPANY, OF MASSACHUSETTS.

DESIGN FOR CARPET-BORDER.

SPECIFICATION forming part of Design No. 31,776, dated October 31, 1899.

Application filed August 31, 1899. Serial No. 729,134. Term of patent 3½ years.

To all whom it may concern:

Be it known that I, WILLIAM A. ELLIOT, a citizen of the United States, and a resident of Yonkers, county of Westchester, and State 5 of New York, have invented a new and original Design for a Carpet-Border, of which the following is a specification.

My design, as shown in the drawing, consists in a new design for the border of a carpet.

The design is characterized, first, by a row 10 of clusters of flowers and foliage supported on an ornamental bar running longitudinally with the border, said clusters being connected by loops, and, second, by two rows of stem-and-spray effects, one or both of which is combined 15 with flowers or ornamental figures. These two outer rows are separated by a conventional line of beading, and outside or beyond said

rows are other conventional ornamental lines. Near the inner margin of the border is a row 20 or line of delicate sprays and flowers and a conventional line of beading. The different rows and lines above referred to are substantially parallel with each other and extend longitudinally with the border. 25

What I claim as new, and desire to secure by Letters Patent, is—

The design for a carpet-border, substantially as described and shown.

In testimony whereof I have signed my 30 name to this specification in the presence of two subscribing witnesses.

WILLIAM A. ELLIOT.
